UNITED STATES PATENT OFFICE.

DONALD BARNS MORISON, OF HARTLEPOOL, ENGLAND.

INDICATING AND RECORDING APPARATUS.

1,335,596.

Specification of Letters Patent. Patented Mar. 30, 1920.

Application filed April 9, 1918, Serial No. 227,543. Renewed February 19, 1920. Serial No. 359,852.

To all whom it may concern:

Be it known that I, DONALD BARNS MORISON, a subject of the King of Great Britain and Ireland, residing at Hartlepool, in the county of Durham, England, have invented the Improvements in Indicating and Recording Apparatus of which the following is a specification.

This invention relates to indicating and recording apparatus and has reference to apparatus of that general character where electrical or other impulses act cumulatively to impart movement to an indicator.

Such apparatus if associated with a clock or timing device can be used for many purposes and in particular if arranged so as to be thrown into and out of operation in accordance with the starting and stopping of mechanism can be used for giving a positive indication of the time during which the mechanism has been in operation.

The object of the present invention is to provide an improved and more generally effective and convenient apparatus which while primarily designed for the aforesaid purpose of determining the periods of activity and inactivity of a machine may be used for other purposes and the invention consists broadly of a device or apparatus comprising an electromagnetic device for imparting through suitable mechanism to a screw, and a saddle or nut like indicator adapted to rest on or against and be actuated by the screw so that its position relative to the screw is a positive indication of the number of impulses imparted to the screw and consequently the position of this indicator at any moment will give the actual time during which the apparatus has been operating. By providing for the starting and stopping of the apparatus in accordance with the starting and stopping of a machine tool, for instance, it follows that the indicator will give the total period during which the machine tool has been in operation. I may so calibrate a surface along which the indicator travels as to show, at a glance the number of hours and (or) the percentage of a given total time, which the machine has been working.

Features of my invention of practical importance which may be specifically mentioned are the provision of means for readily resetting the indicator to zero, and the provision for indicating separately for desired periods as for example for day and

night shifts, which latter involves the provision of means for transferring the impulses either electrically or mechanically from one screw or another at the end of each shift or period, or for transferring one screw from one indicator to another at the end of each shift or period.

In the accompanying drawings I have illustrated one practical embodiment of the invention which it will be understood is given by way of example only and does not exhaust the possible forms my invention may take within the scope of the appended claims. In these drawings—

Figure 1 is a front elevational view partly in section of a device constructed in accordance with my invention.

Fig. 2 is a sectional view thereof on the line A—A of Fig. 1.

Figs. 3 and 4 are side and plan views respectively to a larger scale of the essential mechanism associated with the screw threaded spindles.

Fig. 5 is a side elevational view of the bracket which carries the electro-magnet and its associated mechanism, and

Fig. 6 is a diagram of the essential electrical connections.

Referring to these drawings I provide a box or case 1 in the front of which slots or guides 2 are provided along which indicators or pointers 3 are constrained to slide and these indicators or pointers 3 are in the form of or are connected to half nuts 90 or screw threaded saddles 4 which engage rotatable screw threaded spindles 5. Each screw threaded spindle 5 is carried by a pivoted bracket 6 which also carries an electro-magnet 7 adapted to be energized periodically by and in accordance with the well known principle of an electric clock as will hereafter more fully appear. The spring controlled armatures 8 of the magnets 7 carry pawl like devices 9 each of which cooperates with a ratchet wheel 10 carried by one or other of the screw threaded rotatable spindles 5. Preferably the electro-magnetic action moves the pawl 9 forward and the spring 11 controlling the armature operates to move the ratchet upon the return movement of the armature. The pawl 9 may be and preferably is provided with a wedge like surface 12 which interengages with another stationary wedge surface 13 so that when not operating it locks the ratchet wheel and also prevents it from being moved

more than one tooth for each impulse of the magnet, and as a consequence the screw threaded spindle 5 is finitely controlled.

The screw threaded spindles are maintained in engagement with the half nuts 4 or the like of the indicators or pointers 3 either by gravity or light springs and it will be understood that rotation of the spindles 5 causes the half nuts 4 and indicators or pointers 3 to travel along them.

Associated with the apparatus is some form of switch 14 operated from the belt shifting or other starting and stopping mechanism of the machine tool or the like, and so arranged that impulses are only sent through the magnet coils when the machine is in operation.

The apparatus can be arranged so that the screw threaded spindles 5 are either horizontally or vertically disposed but the latter is preferable since with this arrangement resetting can be effected by simply moving the screw threaded spindles about their pivotal support sufficiently to disengage them from the indicator nuts when the latter will at once fall to zero position. This is illustrated in Figs. 1, 2 and 3, upon reference to which it will be seen that the pivoted brackets 6 are mounted upon a common rod 15 and are provided with notches 16 and a plate 17 carried by a rotatable shaft 18 is provided and it will be readily understood that by turning this plate to engage the notches all the brackets 6 can be turned sufficiently about the rod 15 to disengage the screw threaded spindles 5 from the nut like devices 4 which will then fall and carry the indicators or pointers with them. The brackets 6 are preferably merely hung upon the shaft 15 and in order to permit of their ready removal and replacement they are slotted as at 6^a and a tapered hole 6^b may be provided in the top plate into which a screw threaded key indicated by dotted lines at 20 in Fig. 2 may be inserted to permit of the brackets 6 and their associated mechanism being easily manipulated when it is desired to remove or replace them.

In operation the indicators are set at zero at the commencement of each day and at all times during the day when the machine tool is in use the day shift indicator operates and the apparatus is preferably associated with a clock and a change over switch S' so that at the end of the day shift the impulses are cut off or transferred to operate the night shift indicators, when such are provided. The calibrations may be permanently engraved upon the surface over which the indicators move or removable cards may be provided. The indicator may also if desirable carry a pencil or other marking device indicated at 19 for making a permanent record on the card. The calibrations on the scale are preferably ar-

ranged for the actual hours of operation—that is to say the meal and the rest times are deducted—so that upon one line 21 of the scale there is a time indication in hours and fractions of hours and the other line 22 of the scale gives the percentage of the total time.

Any number of devices may be carried side by side upon the rod or shaft 15. The method of using the device will be clear upon reference to Fig. 6. Every half minute or other predetermined period the clock C which may be an ordinary electric clock completes the circuit of the battery B by closing the switch S subject to the starting switch 14 being closed. This switch 14 is associated with the starting lever L of the machine tool it is desired to time so that there will only be a complete circuit through the magnets 7 every half minute and then only if the switch S is closed, which means of course, if the machine tool is in operation. It will be appreciated that in some types of apparatus the impulses may be imparted mechanically instead of electrically particularly where such an apparatus is employed as a revolution counter or an apparatus where the impulses are imparted by hand may be provided for ordinary counting and checking purposes.

What I claim is:—

1. A cumulative indicator comprising a chart, a pointer movable relative to said chart, a nut like device associated with said pointer, a screw engaging and actuating said nut like device, an electro-magnet having a movable armature, means for closing the circuit through said electro-magnet at predetermined intervals, and means for utilizing the movement of the armature of said electro-magnet to impart movements to said screw.

2. A cumulative indicator comprising a chart, a pointer movable relative to said chart, a nut like device associated with said pointer, a screw engaging and actuating said nut like device, an electro-magnet having a movable armature, a clock, a switch associated with said clock and operating periodically and synchronously with said clock to close circuit through said electro-magnet at predetermined intervals, and means for utilizing the movement of the armature of said electro-magnet to impart definite movements to said screw.

3. A cumulative indicator comprising a chart, a pointer movable relative to said chart, a nut like device associated with said pointer, a screw engaging and actuating said nut like device, an electro-magnet having a movable armature, a clock, a switch associated with said clock and operating periodically and synchronously with said clock to close circuit through said electro-magnet at predetermined intervals, a second switch as-

sociated with the controlling means of a machine for preventing closure of the circuit through said electro-magnet except when said handle is in position corresponding to the running of the machine, and means for utilizing the movement of the armature of said electro-magnet to impart definite movements to said screw.

4. A cumulative indicator comprising a chart, a pointer movable relative to said chart, a nut like device associated with said pointer, a screw engaging and actuating said nut like device, an electro-magnet having a movable armature, a pivotally supported bracket carrying said screw and said electro-magnet, means for closing the circuit through said electro-magnet at predetermined intervals, and means for utilizing the movement of the armature of said electro-magnet to impart movements to said screw.

5. A cumulative indicator comprising a chart, a pointer movable relative to said chart, a nut like device associated with said pointer, a screw engaging and actuating said nut like device, an electro-magnet having a movable armature, a pivotally supported bracket carrying said screw and said electro-magnet, having its center of gravity disposed so as to bias said screw to its operative position engaging said nut, means for moving said bracket about its pivot to disengage said screw from said nut to permit said nut to fall by gravity to zero position, means for closing the circuit through said electro-magnet at predetermined intervals, and means for utilizing the movement of the armature of said electro-magnet to impart movements to said screw.

40 6. A cumulative indicator comprising a pointer movable relative to a chart, a nut like device actuating said pointer, a pivotally supported screw engaging and actuating said nut like device, means for imparting predetermined rotary motion to said screw, and means for moving said screw about its pivot for disengaging said screw from said nut like device to permit resetting of said pointer in zero position.

50 7. A cumulative indicator comprising a chart, a pointer movable relative to said chart, a nut like device associated with said pointer, a screw engaging and actuating said nut like device, an electro-magnet having a movable armature, means for closing the circuit through said electro-magnet at predetermined intervals, a ratchet rigidly connected to said screw, and a pawl associated with the armature of the electro-magnet for coöperating with said ratchet to impart movements to said screw.

8. A cumulative indicator comprising a chart, a pointer movable relative to said chart, a nut like device associated with said pointer, a screw engaging and actuating

said nut like device, an electro-magnet having a movable armature, a spring biasing said armature to retracted position, means for closing the circuit through said electro-magnet at predetermined intervals, a ratchet rigidly connected to said screw, and a pawl associated with the armature of the electro-magnet for coöperating with said ratchet under the influence of the spring to impart movements to said screw.

75 9. A cumulative indicator comprising a pointer movable relative to a chart, a nut like device associated with and moving said pointer, a screw engaging said nut like device, electrical means for periodically actuating said screw, a clock, a switch controlled by said clock for regulating the periodic actuation, and a master switch associated with the starting device of a machine for completing circuit through said electrical actuating means subject to periodic control by said clock.

80 10. A cumulative indicator comprising a pointer movable relative to a chart, a nut like device associated with and moving said pointer, a screw engaging said nut like device, electrical means for periodically actuating said screw, a master switch associated with the starting device of a machine for completing circuit through said actuating 95 means only when said starting device is in position corresponding to the running of the machine, a clock, and a switch controlled by said clock operating to close a circuit through the actuating means periodically 100 subject to control by said master switch.

11. A cumulative indicator comprising a pair of pointers movable relative to a chart, a nut like device associated with and moving each of said pointers, a pair of screws each engaging one of said nut like devices, electrical means for periodically actuating said screws, a clock, a switch controlled by said clock for regulating the periodic actuation, a master switch associated with the 105 starting device of a machine for completing circuit through said electrical actuating 110 means subject to periodic control by said clock.

115 12. A cumulative indicator comprising pointers movable relative to a chart, nut like devices associated with and moving said pointers, screws engaging said nut like devices, electrical means for periodically actuating said screws, a master switch associated with the starting device of a machine for completing circuit through said actuating 120 means only when said starting device is in position corresponding to the running of the machine, a clock, and a switch controlled by said clock operating to close a circuit through the actuating means periodically 125 subject to control by said master switch.

13. A cumulative indicator comprising a chart, a pointer movable relative to said 130

chart, a nut like device associated with said pointer, a screw engaging and actuating said nut like device, an electro-magnet having a movable armature, a fixed shaft, a bracket 5 movably and pivotally suspended on said shaft carrying said screw and said electro-magnet, an opening in the upper part of said bracket, means for engaging said opening to permit said bracket and its associated 10 mechanism to be removed, means for closing the circuit through said electro-magnet at predetermined intervals, and means for utilizing the movement of the armature of said electro-magnet to impart movements to 15 said screw.

14. A cumulative indicator comprising charts, pointers movable relative to said charts, nut like devices associated with and

moving with said pointers, screws engaging and actuating said nut like devices to move 20 said pointers, electro-magnets having movable armatures for imparting movements to said screws, separate brackets each carrying a screw and an electro-magnet, suspension members integral with said brackets, a common shaft upon which all said brackets are pivotally suspended side by side, and means for closing circuit through said electro-magnets periodically. 25
